UNITED STATES PATENT OFFICE

2,222,709

RADIO RECEIVER

George W. Fyler, Stratford, Conn., assignor to
 General Electric Company, a corporation of
 New York

Application November 2, 1938, Serial No. 238,417

8 Claims. (Cl. 250—20)

My invention relates to radio receivers and particularly to such receivers employing loop antennae.

In copending applications Serial No. 211,428 of Arthur G. Manke, filed June 2, 1938, entitled Signal system, and assigned to the same assignee as my present application, is shown a radio receiver employing both a loop antenna and also a vertical antenna such as the usual outdoor antenna used in connection with ordinary household receivers. Switching means are employed alternately to connect the loop and the vertical antenna to the receiver. Such receivers have proven highly popular for home use and one of the objects of my present invention is to simplify its structure and to reduce the cost of its manufacture.

A further object of my invention is to provide means whereby the input transformer commonly used between the receiving vertical antenna and receiver is eliminated and whereby the vertical antenna may be employed, and adapted for optional use, by adding to the receiver only a minimum number of circuit elements over those required for use of the loop for reception. Such simplification of the receiver is highly desirable especially in such a receiver in which the loop is mainly employed as the receptor of the system.

A further object of the invention is to effect such simplification and, at the same time, to provide means whereby the vertical antenna is effective in all bands or only in certain bands as desired.

The novel features which I believe to be characteristic of my invention are set forth with particularity in the appended claims. My invention itself however, both as to its organization and method of operation together with further objects and advantages thereof may best be understood by reference to the following description taken in connection with the accompanying drawing in which the single figure represents the embodiment of my invention.

Referring to the drawing I have shown at 1 an antenna of the so-called vertical type. When I speak of a vertical antenna I have reference to the ordinary capacitive antenna such as is commonly used in connection with household receivers and which commonly are mounted in an elevated position out of doors.

At 2 I have conventionally represented a loop antenna. This loop may be the type shown in the above referred to Manke application and comprises a coil of wire wound upon a suitable nonconducting support and which is housed bod-

ily within an electrostatic shield 3. This shield as shown in that application comprises side walls of vertical conductors insulated from each other except at one end, and conducting end walls, which may be of sheet copper. The vertical conductors of the side walls, which are woven with horizontal nonconducting strands into a fabric, are all connected to one of the end walls and one of them only is connected to the opposite end wall whereby the flow of currents in the shield comprising such conductors is substantially prevented while the shield at the same time operates efficiently electrostatically to shield the loop 2. This loop 2, is also arranged to be oriented, as by rotation with the shield as a unit, 15 to a direction in which the reception of undesired noise currents is a minimum.

This loop as shown in the drawing is connected between ground at 5 and the grid of an electron discharge device 6 through a pair of switches 7 and 8, the cathode of the discharge device being grounded at 9. It is tuned to a desired frequency by means of a condenser 10.

The electron discharge device 6 may be the first stage of a radio receiver, and may comprise 25 a radio frequency amplifier or the conventional superheterodyne converter of the system. Only its grid and cathode are shown but it will of course be understood that this discharge device is of any suitable type used for the purpose 30 mentioned.

Condenser 10 may be the usual uni-control condenser of the ordinary tuned radio frequency or superheterodyne radio receiver. If the receiver be one of the tuned radio frequency type 35 this condenser is uni-controlled with the condensers in the input circuit of the other amplifiers in the cascade connection. If the receiver be one of the superheterodyne type this condenser is uni-controlled with the tuning condenser of the local oscillator and with such other variably tuned radio frequency circuits as may be employed in the receiver. One such condenser is indicated at 10'.

Switches 7 and 8 are the conventional band change switches of the receiver and are arranged as indicated by the dotted line 11, for uni-control movement through three positions. These positions are indicated by the letters B, C and D as applied to the two switches. As shown in 50 the drawing, these switches are in their position B in which the loop 2 is connected between the grid and cathode of the discharge device. This is the position in which the receiver is arranged for operation in the usual broadcast range of 55

frequencies, this range extending from 550 kilocycles to 1500 kilocycles.

For operation of the receiver in a higher frequency band, switches 7 and 8 may be operated 5 to position C. In this position the antenna 1 is connected through switch 7 and a winding 12 to ground. This winding 12 is the primary winding of a transformer having a secondary winding 13, which is connected through switch 8 between 10 the grid and cathode of the discharge device, and which is tuned by the condenser 10 to the received frequency, condenser 14 of course being the usual trimmer condenser, which is connected across the secondary winding.

15 If a still higher band of frequencies is to be received switches 7 and 8 may be operated to position D thereby connecting winding 15 between the antenna and ground and winding 16 between the grid and cathode of the discharge 20 device, these windings being respectively the primary and secondary windings of a transformer adapted for operation in a still higher frequency band. It is tuned to this still higher frequency by condenser 10 and is trimmed in the usual way 25 by trimmer condenser 17.

A further switch 20 is shown as having two positions. In the position illustrated it connects the antenna 1 to the shield 3 of the loop, one terminal of the loop 2 being also connected to 30 the shield. At the opposite position of the switch the antenna is connected to an intermediate point 21 on the loop 2 and currents in it thus flow through the lower portion of the loop 2 to ground. In this way these currents are trans- 35 formed by means of the loop 2 acting as an auto-transformer and are caused to induce voltages between the grid and cathode of the discharge device.

The purpose of switch 20 may, of course, be 40 served by mere clips arranged within the receiver to which the antenna may be connected when installed, but if desired, may comprise a double-throw switch arranged for convenient manual operation.

45 With switch 20 in the position shown the antenna and shield are connected to ground and thus are ineffective to intercept radio waves in space. The shield, of course, operates electrostatically to shield the loop 2 and thus reduce 50 reception of undesired noise current.

It may occur, however, in a particular installation that noise currents are not sufficiently intense to be the predominant consideration and that the stronger reception from the vertical 55 antenna is desirable. This may be effected merely by operating switch 20 to the upper position whereby the loop 2 acts as a step-up transformer between the vertical antenna 1 and the circuit of the discharge device. By utilizing this 60 loop as the input transformer the necessity for a separate input transformer for use between the antenna and the input of the discharge device for reception of frequencies in the broadcast band is avoided. By properly choosing the point 65 21 upon the loop 2 very desirable reception may be had without disturbing the tuning of the loop. If the intermediate point be chosen too far removed from the grounded end of the loop the capacity of the antenna may so effect the input 70 circuit of the discharge device 6 that its tuning may no longer be controlled by the uni-control condensers of the set. That is, the so-called tracking of the uni-control condensers is not satisfactory. I have found, however, that very 75 satisfactory operation of the loop as a trans-

former may be had without material disturbance of the tuning of the loop over the broadcast band by choosing the point 21 relatively close to the grounded end of the loop.

With switches 7 and 8 in the C position the 5 circuit of the loop is opened at switch 8 and the loop, with its shield 3, and antenna 1 all operate as a vertical capacitive antenna in the higher frequency band. This is also true when switches 7 and 8 are in the position D.

10 It is thus seen that with switch 20 in the position shown the antenna 1 is ineffective in the B band but is effective in bands C and D. Antenna 1 is effective in all bands when switch 20 is in the upper position.

15 It may happen, however, that reception at a certain frequency in one of the higher frequency bands, when switch 20 is in its upper position, is rendered unsatisfactory by reason of resonance of the loop at the particular frequency. In one 20 practical installation it was found that reception was unsatisfactory for this reason, at 12 megacycles, which was a frequency in the D band of frequencies to be received. To avoid this difficulty switch 8 may be provided with a stationary 25 contact 22 and a movable contact 23 connected and arranged to short circuit the loop when the band switch 7, 8 is adjusted for operation in the D band. This movable contact, which is actuated by the armature of switch 8 bridges contacts B and 22 when the switch is in the D position thereby short circuiting the loop and rendering the vertical antenna effective irrespective of any resonance in the loop itself.

30 While I have shown a particular embodiment 35 of my invention it will of course be understood that I do not wish to be limited thereto since different modifications may be made and I anticipate by the appended claims to cover any such modifications as fall within the true spirit 40 and scope of my invention.

What I claim as new and desire to secure by Letters Patent of the United States is:

1. The combination, in a radio receiver of an 45 electron discharge device having a grid and cathode, a loop antenna connected between said grid and cathode to supply signals intercepted by said loop to said electron discharge device, one side only of said loop antenna being grounded, and a vertical antenna connected to an intermediate point on said loop near the grounded 50 end thereof whereby additional energy is intercepted by said vertical antenna and supplied through said loop to said discharge device, the portion of the loop between said intermediate 55 point and ground acting to induce electromotive force received on the vertical antenna into the circuit of said loop and discharge device.

2. The combination, in a radio receiver, of an 60 electron discharge device having a grid and cathode, a loop antenna having terminals connected respectively to said grid and cathode, the terminal of said loop antenna connected to said cathode being grounded, the other terminal being effectively ungrounded and a vertical antenna 65 connected to an intermediate point on said loop whereby energy is received from both the loop and vertical antenna, means to tune said loop over a range of frequencies, said intermediate point being chosen sufficiently close to 70 the grounded end of said loop to prevent material disturbance of the tuning of said loop by the capacity of said vertical antenna while producing materially increased reception due to step-up transformer action in said loop between the cir- 75

cuit of said vertical antenna and the circuit of said loop.

3. The combination in a multiband radio receiver, of an antenna, an electron discharge device, a transformer connected between said antenna and discharge device and tuned by a condenser for operation over a certain frequency band, a loop, switching means to disconnect said transformer from said antenna and discharge device and to connect said loop to said discharge device and condenser, said condenser being adapted to tune said loop over a different frequency band, and means to utilize said loop to transform electromotive forces received on said antenna in said different frequency band and to supply said electromotive forces to said discharge device.

4. The combination, in a multiband radio receiver of an antenna, an electron discharge device, a condenser, a transformer connected between said antenna and discharge device and tuned by said condenser for operation in a certain frequency band, a loop adapted for operation in a different frequency band, switching means to disconnect said transformer from said antenna, discharge device, and condenser, and to connect said loop to said discharge device, and condenser, said condenser being adapted to tune said loop and means to connect said antenna to an intermediate point on said loop.

5. The combination, in a multiband receiver, of an antenna, a loop, means to connect said loop to said receiver for reception in a certain frequency band and to connect said antenna to said receiver through a coupling device for reception only in another frequency band, additional means to connect said antenna to said receiver through said loop for reception therefrom in said certain frequency band when said loop is also utilized for reception, and a tuning condenser connected to produce resonance with said loop in said certain frequency band and with said coupling device in said other frequency band.

6. The combination, in a multiband receiver, of an antenna, a loop, means to connect two terminals of said loop in circuit with said receiver for reception of waves intercepted by said loop

having frequencies in a certain range, means to couple said loop to said receiver for operation in a different range, means to connect said antenna to said receiver through said loop for reception in a different frequency range, and means to short circuit said loop to prevent resonance in the loop from interfering with reception in said different frequency range.

7. The combination, in a radio receiver of an electron discharge device having a grid and a cathode, said cathode being connected to ground, a loop antenna having one terminal connected to said grid and the other terminal connected to said cathode, a variable condenser connected across said loop, a second tuned circuit in said receiver including a condenser, said condenser being unicontrolled to vary the tuning of said circuit and said loop in alignment with each other, and means to increase reception of energy by said receiver, said means comprising a capacitive antenna connected to an intermediate point on said loop, said intermediate point being positioned sufficiently far from said terminal connected to said cathode materially to increase reception of radiant energy but insufficiently far to cause the tuning alignment of said loop and tuned circuit upon uncontrolled variation of said condensers to be disturbed by the capacitance of said capacitive antenna.

8. In combination, an electron discharge device, having a grid and cathode, a loop antenna connected between said grid and cathode, said loop antenna being arranged for orientation for minimum response to undesired noise currents, a capacitive antenna having substantially uniform response in all directions, and means alternatively to connect said capacitive antenna to ground through a portion of said loop substantially exclusively to other portions of said loop, whereby currents intercepted by said capacitive antenna are supplied to said discharge device through auto transformer action of said loop thereby producing reception from all directions, and to disconnect said capacitive antenna from said loop.

GEORGE W. FYLER.
